Patented Feb. 10, 1925.

UNITED STATES PATENT OFFICE.

CLEMENT S. CLARKE AND RUPERT W. LOWE, OF SHREVEPORT, LOUISIANA.

ADJUSTER-GRIP DEVICE FOR PUMPING EQUIPMENT.

Application filed September 17, 1923. Serial No. 663,267.

To all whom it may concern:

Be it known that we, CLEMENT S. CLARKE and RUPERT W. LOWE, citizens of the United States, residing at Shreveport, in the parish of Caddo and State of Louisiana, have invented certain new and useful Improvements in Adjuster-Grip Devices for Pumping Equipment, of which the following is a specification.

16 This invention relates to improvements in means for adjustably connecting walking beams of pumping equipment to the polish or pump rod.

15 A further object of this invention is the provision of an adjuster grip device for pumping equipment, such as is set forth in our co-pending application Serial Number 604,324, filed December 1, 1922, and embodying a novel means for adjustably connecting the coupling rod to the polish rod.

20 A further object of this invention is the provision of novel means for adjustably connecting rods or like elements so that the same may be quickly adjusted into firmly connected anti-slip coupled relation.

25 Other objects and advantages of this invention will be apparent during the course of the following detailed description.

In the accompanying drawings, forming a 30 part of this specification, and wherein similar reference characters designate corresponding parts throughout the several views.

Figure 1 is a fragmentary side elevation of pumping equipment, showing more particularly the association of the improved adjuster grip with the walking beam and pumping rod details thereof.

Fig. 2 is a fragmentary side elevation of 40 the improved adjuster grip device.

Fig. 3 is a fragmentary view, partly in cross section; taken at right angles to the view illustrated in Figure 2.

Fig. 4 is a transverse cross sectional view 45 taken substantially on the line 4-4 of Figure 3.

Fig. 5 is a transverse cross sectional view taken substantially on the line 5-5 of Figure 2, and showing a novel clamping arrangement as used in connection with the improved adjuster grip device.

Fig. 6 is a plan view of improved details of this invention.

Fig. 7 is a perspective view of a novel

wedge member used in connection with this 55 invention.

In the drawings, wherein for the purpose of illustration is shown but the preferred embodiment of this invention the letter A may generally designate pumping equipment ordinarily utilized in connection with the pumping of oil, which embodies an improved adjuster grip device or coupling arrangement B.

The pumping equipment A preferably includes the supporting standard 10 upon the upper end of which the walking beam 11 is oscillatively mounted intermediate its ends for operation by any approved means 12. The polish or pumping rod 15 is reciprocally mounted within a casing or tube 16 ordinarily provided therefor, for pumping of oil or the like, in accordance with well known principles. The improved device B is utilized for operative connection of the 75 polish or pumping rod 15 to the walking beam 11.

Referring to the improved device B, the same preferably includes a novel coupling or connecting rod 20, of a single piece of durable metal, preferably being polygonal shaped in cross section, and solid throughout its length. This rod 20 includes an intermediate straight body portion 21; an upper straight portion 22 offset as by a diagonal 80 portion 23 from the run of the intermediate portion 21; and a lower straight portion 24, relatively shorter than the upper straight portion 22, offset from the intermediate portion 21, as by a diagonal portion 25. The 90 upper and lower portions 22 and 24 respectively are offset from the same side of the intermediate or body portion 21, and are offset at different distances; the upper portion 22 being offset for the greater distance. 95

Means 30 is provided upon the upper portion 22 of the coupling rod 20 for oscillatively connecting the same to the walking beam 11. This means is preferably identical with the construction set forth in our co-pending application above referred to, and embodies a cross head 32 providing a body portion 33 which has a squared or polygonal shaped opening 34 therein for receiving the free squared end 22; the latter having 100 shoulders 35 thereon to affix the cross head 32 in position. Cylindrical shaped trunnions 38 and 39 are preferably integral with 105

the body 33, as a part of the cross head, extending in opposite directions and in aligning relation. These trunnions are adapted to rest in depressions provided in a split end 5 of the walking beam 11, as can readily be seen from Figure 1 of the drawings. Reinforcing ribs 40 may be provided along the tops of the trunnions 38 and 39, extending longitudinally thereof. A staple 45 may be 10 carried by the cross head 30, by lateral extensions or wings 41, substantially as illustrated in Figure 2 of the drawings, so that the same may receive a supporting hook or like element, as can well be understood by 15 those skilled in the art to which this invention relates.

Novel means 50 is provided at the lower end of the coupling rod 20 for clamping the same to the pumping rod 15. This means 20 50 includes a clamping ring 51 and a wedge member 52. The remotest offset face of the lower portion 24 of the coupling rod 20 is longitudinally grooved in V-shaped manner, as at 53, and within which the pumping rod 25 15 may fit. The clamping ring 51 is preferably of rectangular formation and of very durable metal. The clamping wedge 52 is preferably of metal and at one side 55 thereof is provided with a V-shaped groove 30 56 extending longitudinally thereof. The opposite side 57 of the wedge 52 is disposed in tapered relation with respect to the side 55 in which the groove 56 is formed.

Referring to the means of connecting the 35 polish rod or pumping rod 15 to the coupling rod 20, it is to be noted that the polish rod 15 is disposed in the groove 53 of the offset end 24 of the coupling rod 20, and when in this relation the axis of the polish rod 15 is in aligning relation with the offset upper end 22 of the coupling rod 20, so that the said axis of the polish rod 15 is in intersecting relation with respect to the axis on 40 which the coupling rod oscillates, as defined by the trunnions or bearings 38 and 39. The clamping ring 50 is then slipped over the offset end 24 of the coupling rod 20 and the pump rod 15, to adjacent the juncture of the diagonal portion 25 of the coupling 45 50 rod 20. The wedge member 52 is then slipped from the top down through the rectangular shaped clamping ring 51, at the opposite side of the polish rod 15 from where the same abuts the coupling rod 20; the groove 56 receiving the polish rod 15. The tapered surface 57 of the wedge 52 then abuts an end of the rectangular shaped ring 51, so that upon forcing the clamp 52 downward into the ring, it is apparent that 55 the polish rod 15 will be securely clamped to the coupling rod 20 in frictional biting relation therewith. Incident to the fact that the grooves 53 and 56 are V-shaped the sharp edges at the juncture of said 60 65 grooves with the surfaces or sides in which

they are formed will bite into the circular polish rod 15, and in clamping relation therewith will hold the pumping rod 15 and the coupling rod 20 in a firm non-slip adjustment.

From the foregoing description of this invention it is apparent that the novel means 50 for connecting the pump rod 15 to the coupling rod 20 will effectively perform the purpose for which the same is provided. It 70 assures a quick adjustable connection of the pump rod 15 to the coupling rod 20, and when once in clamping relation will hold the pump rod 15 against liability of any slipping action whatsoever with respect to the coupling rod 20. The portions 21, 22 and 24 of the coupling rod 20 are of course in parallel relation; the intermediate portion 21 being the longest to permit of a 75 considerable adjustment of the pumping rod 15 80 with respect to the coupling rod 20.

Various changes in the shape, size, arrangement of parts may be made to the form of invention herein shown and described, without departing from the spirit of the 90 invention or the scope of the claims.

We claim:

1. As an article of manufacture a coupling rod for pumping equipment including an intermediate portion, and upper and lower 95 portions relatively offset from the intermediate portion.

2. As an article of manufacture a coupling rod for pumping equipment including an intermediate straight body portion, and upper 100 and lower straight portions offset from the same side of the intermediate portion.

3. As an article of manufacture a coupling rod for pumping equipment comprising an intermediate relatively long portion, an upper portion laterally offset in parallel relation with respect to the intermediate portion, and a relatively short lower portion offset 105 from the intermediate portion.

4. As an article of manufacture a coupling 110 rod for pumping equipment comprising an intermediate portion, an upper straight portion offset laterally from a side of said intermediate portion, and a lower relatively straight portion offset from the same side of 115 the intermediate portion but for a less distance than the upper portion.

5. An adjuster grip device for pumping equipment comprising a coupling rod having upper and lower offset ends, and an adjustable clamping device carried by the lower 120 end of the coupling rod.

6. In combination with pumping equipment including a walking beam and pumping rod, of a coupling rod, having offset 125 upper and lower end portions, the upper end portion being offset to a greater extent than the lower end portion; means connecting the offset upper end portion of the coupling rod to the walking beam, a ring for receiving 130

therethrough the offset lower end portion of the coupling rod and the pump rod, and a wedge for adjustable disposition in the ring for engaging the pump rod and securing the pump rod and coupling rod in side to side connected relation with the pump rod disposed approximately directly below the offset upper end portion of the coupling rod.

7. In combination with pumping equipment including a pump rod, of a coupling rod having the lower end thereof offset and provided with a longitudinal groove in a

side of the offset to receive the pump rod therein, a ring shaped member for receiving the coupling rod at the offset end and the pump rod therein, and a clamp wedge member having a groove therein for receiving the pump rod therein at a side thereof opposite to the grooved face of the coupling rod, said wedge member adapted to clamp the pump rod between the same and the coupling rod offset end within said ring.
